FULLING

Ezekiel J. Wilson, Slingerlands, N. Y., assignor to
 F. C. Huyck & Sons, Rensselaer, N. Y., a corporation of New York

Application March 8, 1944, Serial No. 525,811

19 Claims. (Cl. 26—22)

My invention relates to the treatment of textile fabrics and particularly to an improved apparatus for fulling woolen fabrics or fabrics formed in substantial part of wool. Such fabrics are usually fulled by running them for a considerable length of time between a pair of rolls while wet or saturated with water or other lubricating solution. Pressure controlled by the operator is applied to the top roll, and the action of these rolls on the fabric running therebetween causes it to contract both in width and length and thus become thicker and denser.

The fabric, as it comes from the fulling mill, is usually in one string. One end thereof is started through the rolls, and immediately thereafter the ends of the fabric are stitched together to form an endless belt or loop in which form the fabric is run through the mill until it is fulled down to the required size. The size is checked from time to time, and when the goods are finished, the loop is cut at the point where the ends of the fabric were originally stitched together and the goods are placed on a truck and conveyed to the site of the next operation. Thus, the present procedure is what might be termed a batch or piece method of treatment.

The principal object of my invention is to provide a method and apparatus whereby fabrics, instead of being fulled in the form of a closed loop or belt, may be fulled in the form of a long string and thus to provide one of a multiple of processing units which may be employed in the continuous treatment of fabrics in this form from the loom to the final drying thereof. Another object is to provide a controlled means for continuously fulling a fabric whereby fabrics requiring substantially different treating times may be handled with equal facility and efficiency. A further object is to provide a processing unit comprising one or more fulling mills of the pusher type together with means for substantially continuously feeding a fabric thereto and progressing it therethrough at a controlled rate.

I accomplish these objects in the manner and by means of the novel elements and the combinations and arrangements thereof described below and illustrated in the accompanying drawings in which—

Fig. 1 is a fragmentary plan view of a push mill embodying my invention;

Fig. 2 is a section of Fig. 3 in about the plane 2—2 with certain portions broken away to show details of construction;

Fig. 3 is a fragmentary elevation view of the

push mill with certain portions broken away and certain portions shown in section;

Fig. 4 is a fragmentary end elevation view of the device with certain portions broken away and other portions shown in section;

Fig. 5 is a fragmentary end elevation view similar to Fig. 4 but showing portions of two mills which handle the goods in series or in sequence; and

Fig. 6 is a fragmentary section of Fig. 3 in the plane 6—6.

Referring to the drawings:

1 is the bed of the mill having a floor 2 thereon and sides 3 forming the tub which is open in the rear. Mounted to oscillate on the shaft 4 are the hammer handles 5, 6 and 7 carrying at their bottoms the hammers 8, 9 and 10, respectively.

At the rear, the horizontal crank shaft 11 is mounted to rotate in the bearings 12, 13, 14 and 15 and is turned by the motor 16 through the pulleys 17 and 18 and the belts 19. The cranks 20, 21 and 22 are connected to the backs of the hammers 8, 9 and 10 by means of the connecting rods 23, 24 and 25, respectively. It is to be understood that the cranks on shaft 11 are disposed to each other at angles of 120°, and that hammer 10 is illustrated in fully retracted position. So far, my device does not differ from the ordinary pusher type of fulling mill. The rotation of the shaft 11 oscillates the hammers about the axis of shaft 4 so that goods to be fulled and which are placed in the tub in front of the hammers are pushed and squeezed against the surface 26 in the usual manner.

Secured to one side of the tub at the front is a bearing 27 in which an element 28 is mounted to reciprocate. A shaft 29, driven from shaft 11 by means of the bevel gears 30, has a crank 31 thereon which is connected to and reciprocates the element 28 through the link 32 which may be lengthened or shortened by means of the turn-buckle 33. Thus, the distance which the reciprocating element 28 moves into the tub, which is the measure of its effective stroke, may be regulated. The outside surface of the reciprocating element 28 which contacts the goods being fulled, as hereinafter described, is faced with wood, as shown at 34 in Fig. 2, but other facing materials which will not stain or otherwise damage the fabric may be used.

Mounted above the bearing 27 is a pair of feeding rolls 35 and 36 between which the fabric to be fulled passes. The shaft 37 to which the roll 35 is secured is mounted in fixed bearings 38, 39 and 40. The shaft 41 to which the roll 36 is se-

cured is mounted in bearings 42, 43 and 44. The bearing 44 is a self-centering bearing, and the bearings 42 and 43 are mounted so they may move slightly about the center of the bearing 44 as an axis to provide a space between rolls 35 and 36 for the fabric. The upper roll is yieldingly urged towards the lower roll by means of springs 47 and the compression exerted by said springs may be regulated by the adjusting screws 45 and 46.

Mounted on the shaft 37 is a sprocket wheel 48, and a sprocket wheel 49 is mounted on shaft 41. A chain 50 which cooperates with both sprocket 48 and sprocket 49, as best shown in Fig. 6, is driven from sprocket 51 which, in turn, is driven through any standard type of variable speed box 52 by means of chain 53 and sprockets 54 and 55; sprocket 55 being secured to and driven by shaft 29. Thus, it will be apparent that both roll 35 and roll 36 are driven, and that the speed thereof may be varied as desired by manipulating crank 61 on the variable speed device 52.

In operation, the fabric 56 which is to be fulled may be brought to the mill in the truck 57 as shown in Fig. 5. The fabric is in the form of a long string which is fed through the rolls 35 and 36. After passing through the rolls it drops down, as shown at 58, in front of the reciprocating element 28 by means of which it is pushed into a mass 59 across the front of the hammers where it is pushed by the hammers against the surface 26. Depending upon the number of hammers in each unit, here illustrated as 3 but which may be one or more, and also upon the character of the goods, one unit may be sufficient to complete the fulling. If such is not the case, other units, a fragmentary portion of one of which is shown at 60 in Fig. 5 may be employed. These units may be identical in all substantial respects with the unit just described.

The rate at which the fabric is pushed through the tub in front of the hammers may be controlled by regulating the distance which the reciprocating element 28 moves into the tub. This element, as illustrated, has a fixed stroke, but its distance from the crank 31 and hence the distance which it moves into the tub may be varied by means of the turnbuckle 33. In a similar way the operation of the unit 60 and any other unit through which the goods may be subsequently passed may be controlled.

It will be apparent that the movements of the reciprocating element 28 must be so synchronized with the movements of the hammer 10 that they do not interfere. Thus, as illustrated, the element 28 projects furthest into the tub when the hammer 10 is fully retracted. As the hammer 10 moves from its fully retracted position towards the front of the machine the element 28 is retracted and moves out of the tub. As soon as the toe of the hammer 10, as it is being retracted, moves out of the path of the element 28, the element 28 may start to move into the tub, and may move in to the limit of its movement and be withdrawn before the toe of the hammer, on its forward or working stroke, again reaches said path.

Where more than one unit is employed, the rate at which the goods are fed to each successive unit will differ because the string of goods becomes shorter and denser as the felting progresses.

While I have described my invention in its preferred embodiment it is to be understood that the words which I have used are words of description rather than of limitation and that changes with-

in the purview of the appended claims may be made without departing from the true scope and spirit of my invention.

What I claim is:

5. In a fulling mill, the combination with an oscillating hammer, of means for progressing a fabric transversely across the path of said hammer.
10. In a fulling mill, the combination with an oscillating hammer, of means for feeding a fabric into said mill in front of said hammer, and means independent of said hammer and said feeding means for moving said fabric through said mill.
15. In a fulling mill, the combination with an oscillating hammer, of means for progressing a fabric transversely across the path of said hammer and means for varying the rate at which said fabric is progressed.
20. In a fulling mill, the combination with an oscillating hammer, of means for feeding a fabric to said mill and means for progressing said fabric transversely across the path of said hammer.
25. In a fulling mill, the combination with an oscillating hammer, of means for feeding a fabric to said mill, means for varying the rate at which said fabric is fed to said mill and means for progressing said fabric transversely across the path of said hammer.
30. In a fulling mill, the combination with an oscillating hammer, of means for feeding a fabric to said mill, means for progressing said fabric transversely across the path of said hammer, and means for varying the rate at which said fabric is progressed.
35. In a fulling mill, the combination with an oscillating hammer, of means for feeding a fabric to said mill, means for varying the rate at which said fabric is fed, means for progressing said fabric transversely across the path of said hammer, and means for varying the rate at which said fabric is progressed.
40. In a fulling mill, the combination with an oscillating hammer, of means for feeding a fabric to said mill, means for progressing said fabric transversely across the path of said hammer, and means for varying the rate at which said fabric is progressed.
45. In a fulling mill, the combination with a plurality of separate tubs each having associated therewith at least one hammer and a mounting therefor adapting said hammer to oscillate in the tub, of means associated with each tub for feeding a fabric in the form of a long string simultaneously to said tubs in series, and means associated with each tub and independent of said hammer and said feeding means for moving said fabric through said mill.
50. In a fulling mill, the combination with a plurality of separate tubs each having associated therewith at least one hammer and a mounting therefor adapting said hammer to oscillate in the tub, of means associated with each tub for feeding a fabric in the form of a long string simultaneously to said tubs in series, means associated with each tub and independent of said hammer and said feeding means for moving said fabric through said mill.
55. In a fulling mill, the combination with a plurality of separate tubs each having associated therewith at least one hammer and a mounting therefor adapting said hammer to oscillate in the tub, of means associated with each tub for feeding a fabric in the form of a long string simultaneously to said tubs in series, means associated with each tub and independent of said hammer and said feeding means for moving said fabric through said mill.
60. In a fulling mill, the combination with a plurality of separate tubs each having associated therewith at least one hammer and a mounting therefor adapting said hammer to oscillate in the tub, of means associated with each tub for progressing a fabric in the form of a long string simultaneously through each of said tubs transversely across the path of the hammer associated therewith.
65. In a fulling mill, the combination with a plurality of separate tubs each having associated therewith at least one hammer and a mounting therefor adapting said hammer to oscillate in the tub, of means associated with each tub for progressing a fabric in the form of a long string simultaneously through each of said tubs transversely across the path of the hammer associated therewith.
70. In a fulling mill, the combination with a plurality of separate tubs each having associated therewith at least one hammer and a mounting
75. In a fulling mill, the combination with a plurality of separate tubs each having associated therewith at least one hammer and a mounting

therefor adapting said hammer to oscillate in the tub, of means associated with each tub for progressing said fabric through said tub transversely across the path of the associated hammer, and means for varying the rate at which the fabric is so progressed.

12. In a fulling mill, the combination with a plurality of separate tubs each having associated therewith at least one hammer and a mounting therefor adapting said hammer to oscillate in the tub, of means associated with each tub for feeding a fabric in the form of a long string simultaneously to said tubs in series, and means associated with each tub for progressing said fabric simultaneously through each tube transversely across the path of the hammer associated therewith.

13. In a fulling mill, the combination with a plurality of separate tubs each having associated therewith at least one hammer and a mounting therefor adapting said hammer to oscillate in the tub, of means associated with each tub for feeding a fabric in the form of a long string simultaneously to said tubs in series, means for varying the rate at which said fabric is fed to each of said tubs, and means for progressing said fabric through each tub transversely across the path of the hammer associated therewith.

14. In a fulling mill, the combination with a plurality of separate tubs each having associated therewith at least one hammer and a mounting therefor adapting said hammer to oscillate in the tub, of means associated with each tub for feeding a fabric in the form of a long string simultaneously to said tubs in series, means associated with each tub for progressing said fabric there-through transversely across the path of the associated hammer, and means for varying the rate at which said fabric is progressed.

15. In a fulling mill, the combination with a

5 plurality of separate tubs each having associated therewith at least one hammer and a mounting therefor adapting said hammer to oscillate in the tub, of means associated with each tub for feeding a fabric in the form of a long string simultaneously to said tubs in series, means for progressing said fabric through each of said tubs transversely across the path of the hammer associated therewith, means for varying the rate at which said fabric is fed to each of said tubs, and means for varying the rate at which the fabric is progressed through each of said tubs.

16. A fulling mill comprising a tub, a hammer, a mounting for said hammer adapting it to oscillate in said tub, means for actuating said hammer, a reciprocating element, a mounting therefor adapting said element to cooperate with a fabric for pushing the same across said tub in front of said hammer, and means for actuating said element in timed relation to the movements of said hammer.

17. A fulling mill comprising a tub, a hammer, a mounting for said hammer adapting it to oscillate in said tub, means for actuating said hammer, means for feeding a fabric in the form of a long string into said tub in front of said hammer, a reciprocating element, a mounting therefor adapting said element to cooperate with said fabric for pushing the same across said tub in front of said hammer, and means for actuating said element in timed relation to the movements of said hammer.

18. The structure set forth in claim 16 together with means for varying the rate at which said fabric is pushed across said tub.

19. The structure set forth in claim 17 together with means for varying the rate at which said fabric is fed to said tub and means for varying the rate at which it is pushed across said tub.

EZEKIEL J. WILSON.
